UNITED STATES PATENT OFFICE.

EDWARD H. MCLOUD, OF COLUMBUS, OHIO, ASSIGNOR TO THE CENTRAL BRASS AND FIXTURE COMPANY, OF SPRINGFIELD, OHIO, A CORPORATION OF OHIO.

BUMPER.

Application filed March 5, 1928. Serial No. 259,060.

My invention relates to bumpers.

It is the object of my invention to provide a shock absorbing supporting plate and a buffer plate or plates forming a relatively 5 broad surface in a single unitary structure.

It is my object to provide such a structure in a cheap and economical manner, eliminating vertical joining and supporting members which are customary to use, to prevent rattling and to lend strength to the structure.

It is my object, by eliminating such members, to not only reduce the expense, but to increase the strength of the composite structure, to improve the appearance and to eliminate 15 duplicate parts as well as to facilitate the finishing of the bumper.

Heretofore it has been the practice to provide a back bar member and front buffer plates joined together by bolts with vertically disposed attaching plates for connecting the buffer bars together to prevent their rattling and to insure their adequate assembly into a composite structure. This necessitated a large number of parts which were apt to be- 25 come loose and rattle, or which did not furnish the strength without increasing the size of the parts which in turn increased the expense. It also necessitated finishing of the bumper in a complicated and expensive way 30 and detracted from the stream line appearance and the refinement of design of an automobile, and these supplemental structures provided ornaments that were frequently out of harmony with automobile design.

It is my object to provide the back bar supporting member in such a manner that it may be easily, permanently and rigidly attached to the front buffer bars and so that it will serve as a connecting member between 40 the bars without the use of bolts, clamps and other equipment.

Referring to the drawings—

Figure 1 is a perspective from the rear of the bumper structure showing it in assembled 45 condition.

Figure 2 is an enlarged rear elevation of one end of the buffer bars and supporting bar.

Figure 3 is a section on the line 3—3 of Figure 1 through the center of the bars.

Figure 4 is a rear perspective showing a modified form of attaching the bars to one another.

Figure 5 is a view similar to Figure 2.

Figure 6 is a section on the line 6—6 of 55 Figure 4.

Referring to the drawings in detail, 1 and 2 represent front bumper bars having an intermediate flat portion and curved ends 3 and 4.

Within these curved ends and overlapping 60 such ends, forming a connecting medium there between, is a rearwardly bent plate 5 constituting one end of the supporting bar 6, which has portion 7 for attachment to the vehicle frame. These ends 5 are welded at 65 8 to the inner surface of the curved ends of the bumper bars 3.

I have provided a cut away section 9 in this plate 5 so that this cut away portion 9 may overlap as at 10 portions of the inner 70 surface of the ends 3 of the bumper bars 1 and 2. This overlapping space is used in area in which material 11 is inserted for welding the plate 5 to the respective bars 1 and 2.

This supporting bar 6 extends from the plate 5 rearwardly as at 12 until it arrives at the flat plate 7 on which a suitable clamp is mounted for attaching to the vehicle chassis. It then extends forwardly as indicated by 80 the portion 13 to the center of the structure where it joins a similar portion 13 through the medium of an intermediate plate 14 that is parallel to the bumper bars 1 and 2 and overlaps partially the inner central walls 85 thereof on the rear side thereof so that the plate 14 can be welded as at 15 to these bars 1 and 2. A central aperture 16 is provided in this plate 14 for facilitating welding as at 17. These welds 15 and 17 provide shoulders for engaging either side of the plate 14 90 so that a rigid, firm and neat structure is provided.

It will be noticed that by this construction I have provided a buffer of great strength 95 and resiliency due to the fact that the bumper bars are arched from points of attachment to points of attachment, that is, from the center to the ends, and as the ends of the bumper bars are arcuate, this provides a 100 resilient bridge structure for absorbing shock.

Likewise, the supporting bar 6 has forwardly extending diverging arms 12 and 13 to form a spaced, truss-like structure with 105 the bumper bars so that the free ends thereof may adequately take the shock.

It is to be understood that I desire to comprehend within my invention such modifications as may be desirable within the scope 110

of my claims to adapt the invention to varying conditions of use.

Having thus fully described my invention, what I claim as new and desire to secure by Letters Patent, is:

1. In a bumper, spaced bumper bars and a supporting bar adapted to overlap the space between the bumper bars and join said bumper bars, being attached thereto at each end and 10 the center.
2. In a bumper, spaced bumper bars and a supporting bar adapted to overlap the space between the bumper bars and join said bumper bars, being attached thereto and 15 formed integrally therewith at each end and the center.
3. In a bumper, spaced bumper bars and a supporting bar adapted to overlap the space between the bumper bars and join said 20 bumper bars, being attached thereto and formed integrally therewith by welding at each end and the center.
4. In a bumper, spaced bumper bars and a supporting bar adapted to overlap the space 25 between the bumper bars and join said bumper bars, being attached thereto and formed integrally therewith by welding on the sides and face of the supporting bar against the rear walls of the bumper bars.
5. In a bumper, a plurality of vertically 30 disposed spaced bumper bars and a supporting bar having its ends and intermediate portion attached thereto in overlapping relationship to space said bars and connect them to the supporting bar.
6. In a bumper, a plurality of vertically 35 disposed spaced bumper bars and a supporting bar having its ends and intermediate portion attached thereto in overlapping relationship to space said bars and connect them to the supporting bar, said supporting bar and bumper bars being welded to one another at their points of attachment to form an integral structure.
7. In a bumper, a plurality of vertically 40 disposed spaced bumper bars and a supporting bar having its ends and intermediate portion attached thereto in overlapping relationship to space said bars and connect them to the supporting bar, said supporting bar and bumper bars being welded to one another at their points of attachment to form an integral structure and the ends of the bumper bars being curved backwardly.
8. In a bumper, a plurality of vertically 45 disposed spaced bumper bars and a support-

ing bar having its ends and intermediate portion attached thereto in overlapping relationship to space said bars and connect them to the supporting bar, said supporting bar and bumper bars being welded to one another at their points of attachment to form an integral structure, the ends of the bumper bars being curved backwardly and the intermediate portions between the central and end attachment between the supporting bar and bumper bars being spaced from one another, said bumper bars being attached to a vehicle adjacent to the points of maximum spacing.

9. In a bumper, a supporting bar and spaced bumper bars, said supporting bar adapted to support and space the bumper bars being mounted in overlapping relationship on the spaced bumper bars, said supporting bar having an aperture bridging the space between the bumper bars and overlapping a portion of the inner surfaces of the bumper bars, and welds in said space overlapping the rear of the bumper bars.

10. In a bumper, a supporting bar and spaced bumper bars, said supporting bar adapted to support and space the bumper bars being mounted in overlapping relationship on the spaced bumper bars, said supporting bar having an aperture bridging the space between the bumper bars and overlapping a portion of the inner surfaces of the bumper bars, and welds in said space overlapping the rear of the bumper bars, and 90 welds on the outside of said supporting bar engaging the rear surface of the bumper bars.

11. In a bumper, a plurality of bumper bars and a supporting bar having its ends overlapping the rear faces of the bumper bars at the ends, the center thereof and welds on either side of a juncture between the supporting bar and the inner surfaces of the bumper bars.

12. In a bumper, a plurality of bumper bars and a supporting bar having its ends overlapping the rear faces of the bumper bars at the ends, the center thereof and welds on either side of a juncture between the supporting bar and the inner surface of the bumper bar, and additional welds in apertures provided within said supporting bar where the apertures overlap the inner surface of the bumper bars.

In testimony whereof I affix my signature.

EDWARD H. McCLOUD.
